UNITED STATES PATENT OFFICE.

WILLIAM G. LAMB, OF WATERLOO, IOWA, ASSIGNEE TO NATIONAL SAFETY DEVICES
COMPANY, OF WATERLOO, IOWA.

SIGNALING APPARATUS.

Application filed April 8, 1928. Serial No. 100,656.

My invention pertains to signaling apparatus, and particularly to that class which includes apparatus for regulating the performance of locomotive or motor vehicle 5 whistle or bell signals, and the object of my present invention is to employ a single starting mechanism in such an apparatus, which may be used by the operator at will in either initiating a predetermined series 10 of significant intermittent signals, or for use independently of such a series, in effecting single or any desired number of voluntary repetitive signals.

Specifically, my said invention embraces 15 improvements in detail upon the signaling apparatus of A. I. Woodring, as shown in his patent application Serial Number 746,097, filed October 24, 1924.

15,000, filed October 21, 1921.

It is not my intention to specifically limit myself to the exact structural details, inform or arrangement, of the device of said application, for the improvements of my invention are applicable to other constructions for the above mentioned purposes, and it is therefore to be understood that changes in the precise embodiment of invention herein disclosed can be made within the scope of what is claimed, as also in the constructions already known with which they may cooperate, and yet remain within the protection of the general combination.

The annexed drawings, therefore, illustrate certain constructions of said Woodring device as a basis for the combination there with of my said improvement.

In said drawings, Fig. 1 is a diagrammatic rear elevation of a whistle signaling apparatus of said Woodring type showing my improved starting means associated therewith, parts of both being removed or broken away. Figs. 2 to 6 inclusive are detail views on larger scales of different devices of said apparatus. Fig. 2 is a front elevation of mechanism of the combination whose function it is to effect automatically a series of predetermined intermittent actuations of the signal, reactively. Fig. 3 is a vertical medial transverse section thereof with parts removed. Fig. 4 is a side elevation of the devices shown in said Fig. 2. Fig. 5 is a vertical central section of the operating valve device for actuating the intermittently performing mechanisms of Figs. 2 to 4. Fig. 6 is a vertical central section of the differential valve device for controlling the com-

munications of a bell motor made a part of the signalling circuits.

The intermittently performing mechanisms of this apparatus are the same as shown in the Woodring application hereinbefore referred to for causing a whistle 1 of a steam or other locomotive to give out audible signals in a predetermined series. The arrangement shown is one appropriated for producing a highway repetitive signaling consisting of two long blasts followed by two short blasts.

The numeral 7 denotes a signal actuator adapted to be driven by means of compressed air or other fluid under pressure. It comprises a closed end cylinder, containing a packed plunger or imperforate piston 11 having a stem 6 protruding through an apertured bearing in one cylinder-head. The outer end of said stem 6 has a link connection 5 with a free end of a terminally pivoted arm 4 which may swing in one direction to press in a valve-stem 3 in a control valve contained in a chamber 2 which governs the whistle 1. 70 75 80

The piston 11 is resiliently reactively controlled by a coiled compression-spring 12 mounted between it and the adjacent cylinder-head. The opposite centrally apertured cylinder-head 10 seats a bored plunger-stem 20 whose bore 21 occasionally effects communication between the inner chamber 18 and the atmosphere. This chamber 18 is within a hollow member 9 which is removably mounted in the end of the cylinder 7 with its inner apertured end plugged at 14.

with its inner apertured end plugged at 14. In the closed end of the chamber part 9 opposite said plug 14 is a bearing opening for the stem 20 which has within the chamber 18 a valve-head 19 kept yieldingly upon its seat by the pressure of a spring 15. An interspace between the part 9 and the cylinder-head 10 communicates by way of a bypass 16 with the medial chamber space of the cylinder 7. The part 9 has an inlet-port 17 leading into its chamber 18 from a conduit 102—100 having a control-valve 98 with a communication 97 to a conduit which receives fluid under pressure from a source not shown. The middle interspace of the cylinder 7 has a port 13 in communication with a conduit 83, and the latter communicates with the upper end of a differential valve chamber 84 whose larger upper chamber 88 contains an imperforate piston 85 110

of greater diameter than a valve-head 91 seated in a lower chamber upon a compression spring 92 which yieldingly keeps it seated, the valves being connected by a stem 90 slidably fitted in a medial chamber 89, with the lower part of the stem narrowed above the valve-head 91 for communication with a lateral port 86 controlled by a ball check-valve 87. The port 86 communicates 5 by way of conduits 94, 95 and a valve-chamber 96 with the source of fluid under pressure above mentioned. The lowermost chamber of the device 84 communicates by way of a port 93 with a conduit 99, and the latter is, by way of the valve-chamber 98, also in communication with said source of fluid under pressure. While the valvular device 84 forms an adjunct to the whistle signaling apparatus, it will be no further 10 described here, as it is used for the control of a bell motor not shown.

The cylinder 7 is pivotally suspended from a hanger coupling 8 fixed upon some convenient support. The cylinder 7 is integral with a casting which also includes a bottom cylinder 74, an intermediate spring-barrel 22, and a rear dash-pot 48, but the latter is not shown in detailed construction. A rotatable shaft 23 is centrally mounted in 15 the spring-barrel 22 and a coiled spiral spring 24 is end connected between said shaft and the inner wall of the spring-barrel at a recess of the latter. Referring to Fig. 2, a discoidal face-plate 27 is mounted loosely upon the outer end of the shaft 23 and has its circumferential edge cut away partially at 30 to provide a pair of relatively wide detents 28 followed by a pair of narrower detents 29. A member is fixedly mounted upon the outer end of the shaft 23 and has a radial projection supplied terminally with a threaded pin which can be releasably inserted in any of an arcuate row of sockets in the plate 27 to connect them in a desired position of relative adjustment in properly tensioning the spring 24. Upon a fixed bracket is mounted a rock-shaft 36 having a fixed depending arm 35. At 33 upon the lower part of said arm is pivotally mounted one end of a finger 32 whose movement downwardly is limited by a shoulder 34 on said arm. A small roller 31 is pivoted on the free end of the finger 32 and is in the path of movements of the detents 28 and 29 on the rotatable plate 27. A short upright arm 37 is fixed on the rock-shaft 36 and contains a threaded contact-pin 38 in an apertured seat in its upper part which is aligned with the reciprocable stem 20 in the cylinder-head 10 of said upper cylinder 7. Referring to Figs. 4 and 1, the numeral 42 denotes an apertured bearing bracket to support an end of the rock-shaft 36, and the numeral 39 denotes a sleeve 40 which is loosely mounted on the rock-shaft

between the bracket part 42 and a sleeve fixed on the rock-shaft which carries said arm 37. One end of the sleeve 39 is recessed at 40 through an arc of its circumference to be traversed by a fixed pin or stud 41 projecting from the rock-shaft 36, which permits the stud to travel in said recess limitedly before engaging the sleeve to rock it with the shaft.

Upon the loose sleeve 39 is fixed an upwardly projecting arm 43. A connecting-rod 63 is pivoted at its opposite ends to and between the upper end of the arm 43 and the forward end of a bracket member 44 terminally fixed upon the upper end of the arm 45, the latter having a pivotal connection with an end of the connecting-rod 64 whose opposite end is pivoted to the top part of the primary or hand-lever 68—72.

The numeral 47 denotes an operating valve device for an imperforate piston 80 in the lower cylinder 74. The piston 80 has a stem 75 controlled yieldingly by a spring 76 connected thereto and engaging one end of one cylinder head 77. The outer end of the stem 75 is pivoted at 78 to one end of a pitman 25, whose opposite end is pivoted at 26 to the face-plate 27.

The opposite end of the cylinder 74 has a port 81 which is in communication with a delivery-port 61 of the valvular device 47 by way of a short conduit 73. The opposite inlet-port 62 of the valvular device is in communication by way of a conduit 101 with the conduits 100 and 97—95 supplying fluid under pressure.

The body of the valvular device 47 contains upper and lower chambers 54 and 59 with a communicating passage 57. A plunger stem 56 in the chamber 54 traverses said passage 57 slidably with its spaced wings and has a valve-head 58 closing the lower end of the passage and controlled by a spring 60 in the chamber 59. Above and vertically aligned with the stem 56 is an axially bored body with medial annular flange engaged by a compression spring in the chamber 54 to yieldingly keep the body in its upper position with the upper end of its bore 53 communicating with the atmosphere. The upper end of this bore is directed to open at the side of the upper diminished part of the body 52, and the upper end of the latter is below and in the path of downward rocking movement of a pressure finger or cam member 46 pivoted at 51 to an arched element 50 fixed upon the body 47. The member 46 is continued upwardly in said rock-arm 45, whose upper end is pivoted to an end of the connecting-rod 64 and carries the fixed bracket-arm 44 hereinbefore referred to. A fixed stop finger on the dash-pot top limits the swinging of the arm 43 in one direction.

The numerals 68—72 denote a sectional

primary operating lever, by the single use of which, when swung oppositely, either the intermittent signaling mechanism is operated, or the mechanism only of the upper cylinder 7 is operated to produce single signals.

The upper section 68 may be a channel-bar to slidably adjustably receive between its edge flanges for longitudinal variations of length of the lever, the lower section 72 which is then secured to the upper section 68 by one bolt 70 and nut 71, the bolt being insertible in any of the longitudinally alined bolt-holes 69. The lever near the upper end of its section 68 is pivoted at 67 to a depending bracket 65 fixed on some support. The near end of the connecting-rod 64 is pivoted to the upper termination of the lever part 68. Studs 66 are fixed in the bracket member at opposite sides of the top of the lever section 68 to limit rocking of the lever oppositely. The lower end of the lever section 72 may be shaped with a handle part to be manually grasped by the engineer.

Operation: When it is desired to produce the above mentioned highway crossing signal in operating the whistle 1, the lever 68—72 is swung in one direction by the operator. By means of the linkages above described, the arm 43 is rocked sufficiently to one side without rocking the rock-shaft 36, due to the recess and stud arrangement at 40 and 41. The arm 45 is simultaneously rocked to cause the cam part 46 to depress the body 52, closing the upper end of the bore 53. This compresses the upper spring 55 and also the lower spring 60 while lowering the valve-head 58 to open its seat, the lower end of the body contracting with the upper end of the stem 56, closing the bore 53, as fluid under pressure passes through the valve-seat and the conduit 73 instantly, into the cylinder port 81 to push the plunger 75 to the right compressing the spring 76. The pitman 25 is thus thrust to the right, rocking the face-plate 27 up so that the detents 29 and 28 successively swing idly up to the end of the finger 32 without rocking the depending arm 35. As the lever 68—72 is at once released by the operator, the different springs of the chamber 47, the cylinder 74, and that in the spring-barrel 22 at 24 react to rock the face-plate 27 oppositely to its first position. The detents 28 and 29 now engage the end of the finger device 32—31 to rock it downwardly as the finger is stopped by the shoulder 34, whereby each detent in passing swings the arm 35 and holds it during an appropriate interval of time limited by its respective width, circumferentially. The arm 37 is rocked likewise to have its pin 38 push in the stem 20. This closes the outer opening of the bore 21, while the valve 19 is unseated, compressing the spring 15, while fluid under pressure passes from the port 17 into the by-

pass 16, thence to the middle interspace, where it thrusts the piston 11 to the left, compressing the spring 12, and by the linkages of the stem 6 operating the whistle signal 1, so that the predetermined intermittent blasts of the whistle are produced for the highway signal.

While said parts are reacting, the springs in the valvular device 47 react in closing the valve 58, lifting the stem 56, while the upper spring 55 pushes up the body 52 to open the bore 53 to the atmosphere, and any retained fluid under pressure in the device escapes to the atmosphere. The said moving parts are thus reset at the end of the series of actuations, ready for another similar series of actuations. The weight of the depending lever 68—72, returning to its center of gravity when released, materially aids in said reactive results, and the lever thus remains in this vertical position until again used by rocking it in either of opposite directions.

The operator, or engineer, often has occasion to produce single blasts of the whistle 1, or a different voluntary set of repetitive signals of any respective durations. He can accomplish this also by the use of this single lever 68—72, by rocking it in an opposite direction. This rocks the arm 43 oppositely and at one limit of its movement where the lower end of the recess wall at 40 engages the stud 41, the rock-shaft 36 is then rocked to cause the arm 37 to press in the stem 20 so that the mechanisms of the cylinder 7 actuate alone the whistle 1. In this action, as the arm 45 is rocked oppositely, it does not act upon the valvular device, so the intermittently acting mechanisms connected to the latter are not operated. The released lever 68—72 swings back to neutral position returning the connected elements to inactive positions.

Having described my invention, what I claim as new, and desire to secure by Letters Patent, is:

1. In an apparatus of the character described, a signaling device, mechanism for actuating said signaling device with a predetermined series of actuations said mechanism including limitedly movable coupled parts entrained between but unconnected with associated elements of the mechanism, an operating valve device also included in said mechanism, a lever suspended swingingly near its upper end, and connections between the upper end of the lever and a movable part of the said valve device and between the lever and one of said movably coupled parts, permitting the lever to be swung to one side to move the last-mentioned coupled part idly while simultaneously shifting said valve device part to actuate the valve and with it said mechanism for producing a series of signals by the signaling device, the lever when swung to the opposite side from its normally pendent position causing

idle movement of said valve device part while simultaneously moving both said coupled parts in a direction to actuate the portion of said mechanism between them and the signaling device to operate the latter to produce a single signal.

2. In an apparatus of the character described, a signaling device, mechanism for actuating said signaling device with a predetermined series of actuations, said mechanism including limitedly movable coupled parts entrained between but unconnected with associated elements of the mechanism, an operating valve device also included in the mechanism, a lever composed of adjustably connected parts suspended swingingly near its upper end, stops fixed at opposite sides of the lever to limit its oppositely swinging movements, and connections be-

tween the upper end of the lever and a movable part of the valve device and between the lever and one of said movably coupled parts, permitting the lever to be swung to one side to move the last-mentioned coupled part idly while simultaneously shifting said valve device part to actuate the valve and with it said mechanism for producing a series of signals by the signaling device, the lever when swung to the opposite side from its normally pendent position causing idle movement of said valve device part while simultaneously moving both said coupled parts in a direction to actuate the portion of said mechanism between them and the signaling device to operate the latter to produce a single signal.

In testimony whereof I affix my signature.
WILLIAM G. LAMB.
